BOAT HULL AND HYDROFOIL COMBINATION

Sighard F. Hoerner, Midland Park, and Malcolm Dick,
Morristown, N.J., assignors to Hydro-Marine, Inc.,
Kirkland, Wash., a corporation of Washington

Filed Sept. 17, 1962, Ser. No. 71,723

Term of patent 14 years

(Cl. D71—1)

Des. 197,822

PAGE 2

FIG. 1 is a side elevational view of a boat hull and hydrofoil combination showing our new design;

FIG. 2 is a front elevational view thereof;

FIG. 3 is a rear elevational view thereof;

FIG. 4 is a bottom plan view thereof;

FIG. 5 is a side elevational view showing the hydrofoil units in raised position;

FIG. 6 is a front elevational view thereof;

FIG. 7 is a rear elevational view thereof; and

FIG. 8 is a bottom plan view thereof.

The side not shown is a mirror image of the side shown.

The dominant features of our new design are shown in full lines.

We claim:

The ornamental design for a boat hull and hydrofoil combination, substantially as shown and described.
